UNITED STATES PATENT OFFICE.

JOHN WICKS, OF CHICAGO, ILLINOIS, ASSIGNOR TO AUTOMATIC ELECTRIC INC., OF CHICAGO, ILLINOIS, A CORPORATION OF DELAWARE.

AUTOMATIC TELEPHONE SYSTEM.

Original application filed July 6, 1921, Serial No. 482,765. Divided and this application filed December 7, 1925. Serial No. 73,553.

The present invention relates in general to automatic telephone systems, but is more particularly concerned with methods of handling long distance calls in such systems; and the general object of the invention is to provide a new and improved toll service trunking system for connecting local subscribers in automatic exchanges with long distance lines either as calling or called subscribers.

A special object of the invention is the provision of a new and improved toll service trunking system containing improved circuit arrangements whereby the toll operators can connect with desired calling or called automatic lines which are equipped with paystations, and whereby such operators can thereafter collect or refund deposited coins as the occasion requires.

This application is a division of Patent #1,633,149 issued to me on June 21, 1927. Those features of the invention which relate generally to the toll service trunking system are claimed herein, while the paystation features are claimed in the prior application referred to.

Referring to the drawings, comprising Figs. 1, 2 and 3, there is shown by means of the usual circuit diagrams the apparatus required to establish a complete connection from a toll line terminating in the jack J, Fig. 1, to a local subscriber's station A, Fig. 3. This apparatus comprises the cord circuit O, Fig. 1, located at the toll operator's position in a toll switching station or office; the two conductor trunk line extending from jack J' in the toll switching office through the relay group D, which is a form of repeater associated with the jack J' and its multiples and which is used for translating ground impulses sent by the operator's calling device to ordinary two wire impulses, to the transmission repeater E, Fig. 2, in a main exchange of the system; the toll first selector F, Fig. 2; and the toll rotary connector H, Fig. 3. The repeater, first selector and connector mentioned are all in the same office or exchange, which as indicated above may be one of the main offices or exchanges of a large multi-office system.

Fig. 4 shows certain connections of the test contacts in a certain level of the connector H which are necessary in order to enable

this connector to give rotary service, the test contact of the fourth to the seventh contacts, inclusive, being those associated with a group of lines. When it is desired to connect with a line in this group the connector H will be operated into connection with the first set of contacts. Should the first line be busy the connector will be automatically operated until connection is made with an idle line in the group. If all the lines in the group are busy the connector will not operate but will maintain itself associated with the first set of bank contacts, transmitting a busy signal to the calling party, and as soon as one of the grounded lines become idle the connector will then operate to select it.

As has been pointed out hereinbefore, a feature of the invention is the provision of suitable arrangements whereby the toll operator can collect or refund coins deposited to pay for a toll connection, and it should be explained that the subscribers' stations, or some of them at least, are provided with coin collecting devices, or paystations, of the well known type which is described in the U. S. Patent to Forsberg, No. 1,043,219. Paystation equipment of this type is shown diagrammatically in connection with the substation A, Fig. 3.

In so far as the measured service features of the present case is concerned it may be considered as an improvement on the system shown in Patents No. 1,616,402 and No. 1,586,057, issued to me on February 1, 1927, and May 25, 1926, respectively. In respect to certain other features of the toll service trunking system the present system is closely related to the system disclosed in Patent No. 1,604,372, issued on October 26, 1926. In view of the fact that the Strowger switch mechanism is employed, the general character of which is well understood, and also because of the description in the patent application above referred to, from which the general purposes of the invention will be easily appreciated, it will be unnecessary to consider in detail the various switches and other parts of the equipment, and the explanation of the operation of the complete system will at once be proceeded with.

In order to describe the operation of the invention it will be assumed that the sub-

scriber at substation A desires to obtain a toll connection, and it will be assumed further that the subscriber has placed the call with the toll recording operator, and that the ticket containing the usual data concerning the desired connection has been forwarded to the toll operator having the cord circuit O, Fig. 1, for completion.

Having extended the connection to the desired distant exchange over one of her toll lines, such for example as the toll line which terminates in the jack J, Fig. 1, and having ordered the proper local line to be connected up in that exchange, the toll operator will next proceed to call the subscriber at substation A by way of the toll service trunking system. Observing that the toll trunk terminating in jack J' is idle, as indicated by the normal position of the visual 30, the operator will insert the calling plug P' of the cord circuit O into the jack J', the calling device key K' being thrown shortly after. Upon the insertion of the plug P' into the jack J', a circuit is completed which extends from ground, by way of the springs 29 of the key K', sleeve of the plug P', sleeve of the jack J', through the resistance 75, and thence through the winding of the line relay 42 of the repeater D to battery. The line relay 42 is energized over this circuit and, upon operating, completes the circuit of the slow acting relay 45. Relay 45, upon energizing, prepares a circuit for relay 40 in the repeater D at armature 66, and at armature 65 completes the circuit of the visuals such as 30 and 31 before the various toll operators in order to inform them that the associated toll trunk is now in use. When the line relay 42 energizes, a bridge is completed across the trunk conductors 70 and 71 of the outgoing toll service trunk which energizes the line relay 151 of the selector F, Fig. 2 over a circuit which may be traced as follows: From battery through the upper winding of the line relay 151, armature 173 and its back contact, normally closed springs controlled by armature 117, normally closed springs controlled by armature 122, upper left hand winding of the repeating coil R, conductor 70, normally closed springs controlled by armature 54, winding of the polarized relay 44, armature 53 and its front contact, trunk conductor 71, lower left hand winding of the repeating coil R, and thence through the normally closed springs controlled by armature 123 to ground. The line relay 151 of the toll first selector F, Fig. 2, is energized over this circuit and, upon operating, completes the circuit of the slow acting relay 152. Relay 152, upon energizing, prepares the impulsive circuits of the first selector F in the usual manner. When the calling device key K' is operated the impulse springs of the calling device S are included in the above

traced circuit of the line relay 42 of the repeater D.

The toll operator will now operate her calling device S in accordance with the telephone number of the subscriber at substation A. When the calling device dial is operated in accordance with the first digit of the number, a series of interruptions is produced in the circuit of the line relay 42 of the repeater D. The line relay 42 de-energizes a plurality of times in response to these interruptions, each time opening the previously traced bridge across the trunk conductors 70 and 71 at its armature 53. In this manner the first series of impulses are repeated to the line relay 151 of the toll first selector F. At each retraction of the armature 52 of the line relay 42, an impulse of current is sent to the slow acting relay 40. Upon energizing, relay 40 provides a bridge across the trunk conductors 70 and 71 at its armature 51 which does not include the winding of the polarized relay 44, and at its armature 50 places a direct bridge across the above mentioned trunk conductors on the left hand side of the condensers so as to prevent the discharge from the condensers, due to dialing, being heard by the toll operator. By the removal of the polarized relay 44 from in bridge of the trunk conductors the impulsive circuit of the line relay 151 of the first selector F is greatly improved.

In the first selector F the circuit of the line relay 151 being opened a plurality of times by the operation of the relay 42 in the repeater D the former relay will retract its armature 166 a corresponding number of times, each time sending an impulse of current to the vertical magnet 175 of the selector F in series with the slow acting relay 153. Magnet 175 operates to raise the switch wipers 183-186, inclusive, step by step until they are placed opposite the level of bank contacts in which are terminated trunk lines leading to the desired group of connector switches. Upon the first off normal step of the first selector F the off normal springs are shifted and a circuit is completed which extends from ground, by way of off normal spring 171 and its working contact, through resistance 138, and thence through the polarizing winding of the electro-polarized relay 103 to battery. The electro-polarized relay 103 does not operate when only its polarizing winding is energized but does so immediately upon the current flowing in the proper direction in its upper winding. The slow acting relay 153 is energized in series with the vertical magnet, and upon the first vertical step of the switch shaft, completes a circuit which extends from ground on release trunk conductor 176, by way of front contact and armature 168, off normal spring 170 and its working contact, and through the winding of the step-
125
130

ping relay 154 to battery. Relay 154, upon energizing, establishes a locking circuit for itself at its armature 169, and at armature 170 prepares a circuit for the rotary magnet 180. Shortly after the termination of the vertical movement of the switch, the slow acting relay 153 deenergizes and the circuit of the rotary magnet is completed, this extending from ground on release trunk conductor 176, by way of normally closed springs controlled by armature 168, armature 170 and its front contact, and thence through the winding of the rotary magnet 180 to battery. Magnet 180 operates to rotate the switch wipers 183-186, inclusive, into engagement with the first set of bank contacts in the selected level and at the same time opens the locking circuit of the stepping relay 154, which deenergizes, opening the circuit of the rotary magnet, which deenergizes also.

Assuming that the trunk line, with which the switch wipers are now in engagement, is busy, there will be a ground potential present upon the test contact engaged by the test wiper 185, and a circuit will be completed which extends from the said grounded test contact by way of test wiper 185, armature 162 and its back contact, back contact and armature 179, off normal spring 170 and its working contact, and through the winding of the stepping relay 154 to battery. Relay 154, upon energizing, establishes a locking circuit for itself and completes the circuit of the rotary magnet. The rotary magnet operates to rotate the switch wipers into engagement with the bank contact associated with the next trunk line in the selected level and at the same time opens the locking circuit of the stepping relay 154, which deenergizes, opening the circuit of the rotary magnet, which deenergizes also. The alternate operation of the stepping relay 154 and the rotary magnet 180 will continue until an idle trunk is found, which, we will assume, is the trunk line terminating in the bank contacts 187-190, inclusive. When the switch wipers are rotated into engagement with this trunk line, there will be no ground potential present upon the test contact 189 engaged by the test wiper 185 and no circuit will be completed for the stepping relay 154. As the switching relay 150 is no longer short circuited, the said relay will be energized over a circuit which may be traced from ground on release trunk conductor 176, through the winding of relay 150, back contact and armature 179, off normal spring 170 and its working contact, and thence through the winding of the stepping relay 154 to battery. It may be mentioned at this point that the relay 150 is of sufficiently high resistance to prevent the energization of the stepping relay 154 in series with it. Relay 150, upon energizing, completes the energizing circuit of the line relay 201 of the toll connector switch at the armature 160 and 164. This circuit may be traced from ground, through the lower winding of the line relay 201 of the connector H, by way of back contact 70 and armature 219, normally closed springs controlled by armature 239, trunk conductor 194, bank contact 190, wiper 186, front contact and armature 164, armature 134 and its back contact, armature 112 and its back contact, lower right hand winding of the repeating coil R, upper winding of the electropolarized relay 103, back contact and armature 121, upper right hand winding of the repeating coil R, normally closed springs 75 controlled by armature 111, back contact and armature 130, armature 160 and its front contact, front contact and armature 165, wiper 183, back contact 187, trunk conductor 191, normally closed springs controlled by armature 235, armature 215 and its back contact, through resistance 220, and thence through the upper winding of the line relay 201 to battery. The electropolarized relay 103 in the repeater E is not energized at this time as the current flowing in its upper winding is not in the proper direction. The line relay 201 of the connector switch H is energized over this circuit, and, upon operating, completes the circuit of the slow acting relay 202. Relay 202, upon energizing, prepares the operating circuits of the connector H at armature 225 and at armature 224 completes a circuit for the ring cut off relay 208. Relay 208, upon energizing, 80 establishes a locking circuit for itself at armature 256, which may be traced from ground at the transmission repeater E, by way of armature 111 and its back contact, armature 161 and its front contact, wiper 184, bank contact 188, trunk conductor 192, armature 256 and its front contact, and thence through the winding of the ring cut off relay to battery. Another result of the energization of relay 208 is that the ringing circuit, which would normally be operative immediately upon the connector H connecting with the called line, is opened, and, by means of the previously traced locking circuit, placed under the control of the toll operator. It will be noted that the trunk conductor 193 is the release trunk conductor and that it has ground placed upon it from the slow acting release relay 152 of the toll first selector F. It will also be noted that the switching relay 150 of the selector F, upon energizing, did not open the circuit of the line relay 151 and therefore this relay remains under the control of the line relay 42 of the repeater D. It will be remembered that the previously traced circuit of the line relay 201 of the connector H includes the armature 165 of the line relay 151. 85

It will now be apparent how the connector H is controlled. When the toll operator 130

operates her calling device in accordance with the next digit of the subscriber's number at substation A, a series of interruptions is produced in the circuit of the line relay 42 and the repeater D and these are in turn repeated to the line relay 151 of the first selector F. At each retraction of its armature 165, the circuit of the line relay 201 is opened and the impulses are thus sent to the line relay 201 of the connector H in order to control its operation. At each retraction of the armature 221 of the line relay 201, a circuit is completed which extends from ground, by way of back contact and armature 217, armature 221 and its back contact, armature 225 and its front contact, off normal springs 228 and 227, through the winding of the vertical magnet 262, and thence through the winding of the slow acting relay 207, to battery. The above is the circuit over which the first impulse to the vertical magnet is transmitted. Upon the first vertical step of the switch, the off normal springs are shifted and the remaining vertical magnet impulses traverse a different circuit, which is the same as the one previously traced, except that it includes the off normal springs 228 and 229, and armature 253 and its front contact, relay 207 being now in an operated position. The vertical magnet 262 operates to raise the switch wipers 270, 273, inclusive, step by step until they are placed opposite the level of bank contacts in which is located the contact set associated with the line of the substation A. The slow acting relay 207 is energized in series with the vertical magnet and maintains its armature attracted throughout the vertical movement of the switch and at the termination thereof deenergizes and prepares the impulsing circuit of the rotary magnet 260.

The toll operator may now operate her calling device in accordance with the next and final digit of the called subscriber's number. As before, the line relay 42 of the repeater D and the line relay 151 of the selector F operate and transmit a series of impulses corresponding to the last digit of the called number to the line relay 201 of the connector H. Relay 201 deenergizes a plurality of times in response to these interruptions each time sending an impulse of current over the following circuit: Ground by way of back contact and armature 217, armature 221 and its back contact, armature 225 and its front contact, off normal springs 228 and 229, armature 253 and its back contact, back contact and armature 247, through the winding of the slow acting relay 206, armature 242 and its back contact, and thence through the winding of the rotary magnet 260 to battery. The rotary magnet operates to rotate the switch wipers 270-273, inclusive, into engagement with the set

of bank contacts associated with the line of the substation A, which, we will assume, are the bank contacts 274-277, inclusive. The slow acting relay 206 is energized in series with the rotary magnet and operates at 70 its armature 251 to connect the test wiper 271 to the test relay 205.

Assuming that the desired line is idle at the present time, there will be no ground potential present upon the test contact 275 engaged by the test wiper 271 and no circuit will be completed for the test relay 205. Then, following the deenergization of the slow acting relay 206, a circuit may be traced extending from ground, by way of front contact and armature 223, back contact and armature 245, lower winding of the switching relay 203, back contact and armature 251, test wiper 271, test contact 275, winding of the switching relay 280 of the line switch C 85 and thence through the winding of the motor magnet 282 to battery. Relays 203 and 280 are energized over this circuit. However, due to a mechanical interlocking device controlled by the armature of the line relay 281, which is now normal, the switching relay 280 only partially attracts its armatures, that is, enough to disconnect the line of the called substation A from its normal battery and ground connections in the line switch C. 95 Relay 203, upon energizing, locks itself to ground on release trunk conductor 193 at armature 237, prepares the circuit of the relay 200 at armature 238, and at armatures 235 and 239 reverses the connections of the line relay 201 with regard to the trunk conductors 191 and 194. As the current flow is now reversed in the upper winding of the electropolarized relay 103 in the transmission repeater E which is included in the circuit of the line relay 201, this relay will be operated. Relay 103, upon energizing, establishes a locking circuit for itself at armature 120, at armatures 122 and 123 reverses connections of the line relay 151 of the first selector F with regard to the trunk conductors 70 and 71, and also at armature 122 connects the alternating current relay 104 across the trunk conductors 70 and 71. The normal current flow over the conductors 70 and 71 being now reversed, the polarized relay 44 in the repeater D is energized. Relay 44, upon operating, completes the circuit of the relay 43. Relay 43, upon operating, establishes a locking circuit for itself at armature 56, 115 at armature 55 places an additional ground upon the conductor which extends to the visuals 30 and 31 and at armatures 54 and 58 short circuits the condensers which are normally included in the trunk conductors 70 and 71, at the same time removes the polarized relay 44 from in bridge across these conductors. The condensers in the trunk conductors 70 and 71 having been short circuited by the operation of the relay 43 in 130

the repeater D, the relay 14 in the bridge of the cord circuit O is energized in series with the line relay 151 of the toll first selector F. Relay 14, upon energizing, completes a circuit for the supervisory lamp L' at its armature 25. By the operation of this signal, the toll operator is notified that connection has been established with the desired line.

10 Returning now to the operation of the electropolarized relay 103 in the repeater E, another result of its energization is that the circuit of the line relay 201 of the connector H is opened at armature 121 and at 15 the front contact of this armature and the front contact of armature 124 the battery feed relay 102 is connected to the conductors 191 and 194 in order to supply talking battery to the called subscriber when he answers. It will be seen that ground through 20 the upper winding of relay 102 stands against ground through the line relay 201 and the battery through the lower winding of relay 102 stands against battery through 25 the line relay 201 hence relay 201 will deenergize. The line relay 201, upon deenergizing, completes the circuit of the relay 200. Relay 200, upon energizing, disconnects the line relay 201 from the trunk conductors 191 30 and 194 at armatures 215 and 219 thereby providing a direct metallic circuit to the called line from the repeating coil R in the repeater E, and at armature 216 opens the original energizing circuit of the ring cut 35 off relay 208.

The next operation is to ring the subscriber at substation A. For this purpose the toll operator momentarily operates her 40 ringing key K⁴ thereby projecting ringing current out on the trunk line comprising conductors 70 and 71 which operates the alternating current relay 104 in the repeater E over a circuit extending from the free pole of the generator G by way of normally closed springs of key K⁶, normally closed springs of key K⁵, working contact and 45 spring 27 of key K⁴, ring of the plug P', ring of the jack J', armature 54 and its front contact, conductor 70, upper left hand winding 50 of repeating coil R, front contact and armature 122. At this point the circuit divides, one path extending through the winding of the alternating current relay 104 to the left hand winding of the repeating coil R, trunk conductor 71, front contact and armature 58, tip of the jack J', tip of the plug P', spring 28 of key K⁴ and its working contact to ground. A second path extends through 55 the high resistance relay 100 to ground by way of armature 116 and its back contact, and the third path extends by way of armature 131 and its back contact, through the resistance 139, armature 115 and its back contact, through the lower winding of the line 60 relay 151 of the first selector F to ground. The relay 100 is of very high resistance and will not be operated by this ringing current. The alternating current flowing through the lower winding of the line relay 151 of the first selector F has no effect on it as a 70 circuit for its upper winding is completed from ground at the working contact of spring 28 of key K⁴ in the cord circuit O. The alternating current relay 104 is operated over the previously traced ringing 75 circuit, and, upon attracting its armature 129, completes the circuit of the relay 101. Relay 101, upon energizing, removes ground from the ringing control conductor 192 at armature 111. This operation opens the 80 locking circuit of the ring cut off relay 208 in the connector H. The latter relay, upon deenergizing, completes the ringing circuit of the called subscriber. The subscriber at 85 substation A will now be intermittently 85 signalled until he responds. When the receiver is removed at the called substation the ring cut off relay 208 is energized over the called subscriber's line loop and, upon operating, reestablishes its former locking 90 circuit to ground on the ringing control conductor 192, the operator having restored her ringing key by this time to permit the deenergization of the relay 101. Relay 208, upon operating, locks itself energized at armature 256, and at armatures 255 and 257 95 opens the ringing circuit and at the front contacts of these armatures finally completes the talking connection. Talking battery is now supplied to the transmitter at 100 substation A from the windings of the battery feed relay 102 in the repeater E. This circuit will not be traced in detail but it will be observed that the lower line conductor extends uninterruptedly back 105 through the connector H and the selector F to the lower right hand winding of the repeating coil R from whence it extends through the lower winding of the battery feed relay 102 to battery, while the upper line conductor 191 extends back through the connector H and the selector F to the upper right hand winding of the repeating coil R from which point it may be traced through 110 the said winding and through the upper winding of the relay 102 to ground. Relay 102 is energized by the current flow over the called line loop, and, upon attracting its armature 114, places an additional ground upon the ringing control conductor 192. 115 Another result of the energization of relay 102 is that the high resistance relay 100 is placed in bridge of the trunk conductors 70 and 71. This bridge may be traced from 120 trunk conductor 70, upper left hand winding of the repeating coil R, front contact and armature 122, winding of the high resistance relay 100, armature 116 and its front contact, resistance 125, armature 123 and its front contact, lower left hand wind- 125 130

ing of the repeating coil R to trunk conductor 71. A further result of the energization of relay 102 is that the line relay 151 is disconnected from the trunk conductors 70 and 71 and a local circuit is completed for it, which extends from ground through the lower winding of relay 151, resistance 136, armature 117 and its front contact, back contact and armature 173, and thence through the upper winding of the line relay 151 to battery. The line relay 151 having been disconnected from the trunk conductors 70 and 71 no battery will be present thereon and there will be no circuit for the relay 14 in the operator's cord circuit for which relay will deenergize to efface the supervisory lamp L'.

The operator will now come in on the line by throwing the listening key K³ and, after observing that the proper person is at the telephone, will request the called party to deposit the coin or coins to pay for his connection. When the coins are deposited, the operator is given an audible signal over the telephone circuit in the usual manner so that she will know that the correct amount has been deposited, and also the polarized magnet of the paystation apparatus is connected to the line in order that the operator may thereafter either collect or refund the deposited coins.

Everything is now in readiness for the conversation to begin, at least so far as connection to the subscriber at substation A is concerned. Assuming that the desired party has been obtained in the distant exchange the operator will now complete the connection at her cord circuit and the connected parties can converse as desired. It will be observed that the connection includes the two conductor trunk line from the toll switching station to the main or local exchange (the trunk comprising conductors 70 and 71) which is a decided economy over former arrangements which sometimes require three or four conductor trunk lines. Another advantage which may be pointed out is in the arrangement by which the called subscriber controls the release of the connection while his receiver is off through the medium of the relay 102 which controls the local circuit of the line relay 151 of the first selector F. This arrangement makes it possible for the toll operator to change cord circuits after the called party has answered without releasing the established connection.

When the conversation is terminated both subscribers will replace their receivers. Upon the replacement of the receiver at substation A the relay 102 in the repeater E is deenergized and the line relay 151 is again connected to the trunk conductors 70 and 71. As a result, the supervisory relay 14 in the operator's cord circuit is energized

and the supervisory lamp L' is lighted to give the operator a disconnect signal. Before releasing the connection the operator will have to collect whatever coins were deposited and this operation will now be explained.

In order to collect the deposited coins the operator will throw the collect master key K⁵ and operate the ringing key K⁴ in the cord circuit O. The keys K⁵ and K⁶ are common to all the cord circuits at the operator's position and, when thrown, serve to connect either of the high voltage batteries B or B' to the generator leads extending to the various ringing keys in the cord circuits. By the operation of the ringing key K⁴ the high voltage battery B is connected to the trunk conductor 70 from whence it flows through the upper left hand winding of the repeating coil R, front contact and armature 122, through the winding of the high resistance relay 100 to ground by way of armature 116 and its back contact. The relay 100 is operated by the high voltage current from the battery B, and, upon energizing, closes the circuit of the slow acting relay at its armature 110. Relay 105, upon energizing, completes a local circuit for the upper winding of the line relay 151 at armature 133 so as to maintain the selector F and connector H in their operated positions, connects the trunk conductor 70 direct to the trunk conductors 191 and 194 by way of the armatures 131, 130, and 134, over the talking conductors and wipers of the selector F and at the same time connects the conductors 191 and 194 to ground by means of the resistance 140 and the condenser at armature 132. Current now flows from the battery B, through the low resistance relay 32, springs of key K⁵, working contact of spring 27 and the said spring, ring of plug P', ring of jack J', conductor 70, front contact and armature 131, front contact and armature 130, armature 160 and its front contact, front contact and armature 165, wiper 183, bank contact 187, conductor 191, front contact and armature 257, armature 239 and its front contact, armature 219 and its front contact, wiper 273, bank contact 277 and thence through the polarized magnet at the subscriber's substation to ground. The current from the battery B flows in the circuit of the polarized magnet in the proper direction to operate it to collect the deposited coin or coins, the paystation mechanism being reset at the same time.

When the circuit through the polarized magnet is established the resulting current flow is sufficient to operate the relay 32 in series with the matter lead from the battery B and this relay, upon operating, closes the circuit of the supervisory lamp L⁵ thereby advising the operator that the collect circuits are operating and that the coins have been

collected. The supervisory lamp L^5 is common to all the cord circuits at the position and notifies the operator of the successful collection or refunding of coins.

5 While it is true that the alternating current relay 104 will energize momentarily due to the charging of the condenser 159 the momentary operation of the armature 129 will have no effect as the relay 105 operates at 10 once and ground is removed from the armature 129.

In order to assure herself that the coins have been collected at the subscriber's substation apparatus the toll operator will operate the key K^4 twice. If everything is 15 functioning properly the coins at the substation will be collected upon the first operation of the key K^4 and, upon the restoration of the key to normal, the polarized magnet at the substation will be disconnected 20 from the line. When the key K^4 is again operated there will be no circuit for the relay 32 and consequently the lamp L^5 will not be lit. As this signal does not operate the 25 toll operator will know that the coins deposited have been collected and she will restore her ringing key to normal and also the master collect control key K^5 .

If the toll operator desires to refund the 30 deposited coin rather than collect it she may do so by operating the master refund key K^6 and then her ringing key K^4 . Assuming that the same connection exists as in the previous case where the operator collected the 35 coins, if the master refund key K^6 is operated the battery lead from the battery B' is connected to the conductor 70. This is a high voltage battery the same as the battery B but it supplies current of the opposite polarity and it follows therefore that the polarized magnet at the substation A will be operated in the opposite direction to refund the deposited coins rather than collect them. Except as pointed out the refunding operation 40 is the same as the collecting operation and the operator is given supervision by means of the lamp L^5 in the same manner as was before described.

Under certain conditions the toll operator 45 may find it desirable to collect or refund deposited coins at substation A before she connects the two parties together for conversation. She may desire to refund the deposited coins in order to assure herself by a repetition of the usual audible signal when 50 the coins are placed in the coin box that the proper amount has been deposited. This operation will now be briefly described. The receiver at substation A being off the switch-hook the battery feed relay 102 in the repeater E will be energized and the high resistance relay 100 will be placed in bridge of the trunk conductors 70 and 71. Now when 55 the toll operator goes through the regular 60 operation of refunding by operating the

ringing key in the cord circuit together with the refund master key K^6 the high resistance relay 100 would be energized over the two trunk conductors 70 and 71 in series. As a result of the operation of relay 100 a 70 circuit is completed for the slow acting relay 105 and the refunding operation from this point on takes place in the same manner as was before described.

The release of the main connection over the toll service trunk is brought about by the removal of the plug P' from the jack J' , at least this is true if the called subscriber has replaced his receiver. In order to explain this more fully it will be assumed that the 80 plug is removed from the jack J' before the subscriber A has hung up. By the removal of the plug P' , the circuit of the line relay 42 of the repeater D is opened and this relay will deenergize but the relay 43 remains 85 locked up. The busy visuals 30 and 31 are thus maintained operated to indicate that the trunk is busy. Now, when the called subscriber replaces his receiver, the relay 102 in the repeater E is deenergized and the 90 line relay 151 of the toll selector F is connected across the incoming trunk conductors 70 and 71, as was explained hereinbefore in connection with the control of the supervision. The effect of this is to energize the 95 slow acting relay 41 which was placed in a bridge across the trunk conductors 70 and 71 by the deenergization of the slow acting relay 45, the latter relay having deenergized shortly after the deenergization of the line 100 relay 42. Relay 41, upon energizing, opens the locking circuit of the relay 43. Relay 43, upon deenergizing opens the circuit through the visual 30 and 31 thus rendering the trunk line idle and also disconnects the slow acting 105 relay 41 from in bridge of the trunk. Relays 41 and 151 are thereby deenergized. The latter relay breaks the circuit of the slow acting relay 152 and also breaks the operating circuit extending to the connector 110 H. The slow acting relay 152, upon deenergizing, completes the release magnet circuit of the selector F at armature 167 and at armature 178 removes ground from the release trunk conductor 192 thereby allowing the relay 203 in the connector H to deenergize. Relay 155 is energized in multiple with the release magnet 181 and is therefore 115 operated during the restoration of the switch. Relay 155 opens a point in the circuit of the upper winding of the line relay 151 at armature 173, and at armature 174 opens a point in the locking circuit of the relay 154 so as to prevent the relay 154 energizing and locking should the test wiper 185 encounter any 120 grounded test contacts during the release of the switch. At the connector H, relay 203 upon deenergizing, opens the circuit of the relay 200. The latter relay, upon retracting 125 its armature 217 closes the circuit of the re- 130

lease magnet 261. In this manner the connector H is restored to normal. Upon the selector F releasing the relay 103 is deenergized as the circuit of its locking winding which has been maintaining the relay armatures attracted after having been operated by the reversal of battery from the connector H, is opened at the off normal springs 171 of the selector F. In this manner all the apparatus used in the connection is restored to normal.

Returning now to the operation of the connector H when engagement was made with the bank contacts associated with the line 15 of the substation A it will now be assumed that this line was busy. Under these conditions, there will be a ground potential present upon the test contact 275 engaged by the test wiper 271. A circuit will thereby be completed for the test relay 205. Relay 205, upon energizing, prepares a locking circuit for itself at armature 246 to ground on the said test contact which is effective immediately following the deenergization of the 20 slow acting relay 206, and at armature 248 places the busy tone from the busy machine 25 places the busy tone from the busy machine on the upper heavy talking conductor 191.

Having called the digits corresponding to the called subscriber's number the toll operator 30 will restore her key K⁷ to normal. As the supervisory lamp L' is not lighted at this time the toll operator will operate her listening key K⁸ in order to ascertain whether or not the desired line is busy. The 35 busy tone which was placed upon the upper heavy talking conductor is now audible to the toll operator and she will restore her listening key to normal and busy herself with other connections while waiting for the 40 desired line to become idle.

When the line of the substation A becomes idle, ground will be removed from the test contact 275 and the test relay 205 will be deenergized to remove the tone from the upper heavy talking conductor and at the same time complete the circuit of the switching relay 203. Relay 203 will be energized as before described and will operate to reverse the battery over the incoming trunk line.

50 By this operation the electropolarized relay 103 in the repeater E is energized and operates in the usual manner to establish a locking circuit for itself and prepare a circuit of the battery feed relay 102. Another result 55 of the energization of relay 103 is that the battery is reversed over the conductors 70 and 71 in the usual manner and the polarized relay in the repeater D operated to short circuit the condensers normally included in 60 these trunk conductors. By this operation the bridged supervisory relay 14 in the operating cord circuit is energized to light the supervisory lamp L', thus notifying the toll operator that the desired line has become 65 idle. In the connector H the relay 200 is

energized and a metallic circuit provided back to the repeating coil R. The operator at the toll board noting the operation of the lamp L' will now operate her ringing key and the called line will be signaled as before 70 described. When the called party responds the battery feed relay 102 will be energized over the called line loop and operate to disconnect the line relay 151 from the trunk conductors 70 and 71. This latter operation 75 causes the supervisory lamp L' in the operator's cord circuit to be extinguished and she will be notified that the connection is completed. The subsequent operations in which 80 the connection is finally completed, the coins collected or refunded, as the case may be, and the connection finally released, will take place in the same manner as was hereinbefore described.

The above is the normal operation of the 85 connector H when engagement is made with a busy line if this line is a private line. However, should the line of the substation A be one of a group of lines the test contacts 275 and 276 thereof will be connected 90 in the manner shown in Fig. 4. Fig. 4 represents a level of bank contacts having private lines and grouped lines, the lines of the group being fourth, fifth, sixth, and seventh 95 bank contacts. These lines are all listed under one number in the directory and when connection is desired with one of these lines the connector H is rotated into engagement with the first line of the group. If this is busy and if there is an idle line in the group 100 the connector H will operate to automatically select it. However, if all lines in the group are busy the connector will remain with its wipers in engagement with the fourth set of bank contacts transmitting a 105 busy signal to the calling subscriber until one of the lines becomes idle. When this occurs the connector will then operate as previously mentioned. This operation of the connector H will now be described. For 110 this purpose it will be assumed that the line of the substation A is the first one of the group of lines and is busy when the connector H is rotated into engagement with the bank contacts 274-277, inclusive. As there 115 is a ground potential present upon the test contact 275, the test relay 205 will be energized. As the test contacts 275 and 276 will be connected together there will also be a ground potential placed upon the test contact 276. Then, following the deenergization 120 of the slow acting relay 206 a circuit may be traced extending from the said grounded test contact by way of test wiper 272, armature 250 and its back contact, armature 265 and its back contact, armature 249 and its front contact, through the winding of the stepping relay 204 and thence through the winding of the slow acting relay 207 to battery. Relay 204, upon ener-

gizing, establishes a locking circuit for itself at armature 240 and at armature 241 completes a circuit for the rotary magnet 260. Rotary magnet 260 operates to rotate 5 the switch wipers 270-273, inclusive, into engagement with the next set of bank contacts and also to open the locking circuit of the stepping relay 204 which deenergizes opening the circuit of the rotary magnet 10 which deenergizes also. If this next line is busy the test relay 205 will be maintained energized and the stepping relay will operate, as before described, to complete the circuit of the rotary magnet and the switch 15 wipers will be rotated into engagement with the next set of bank contacts. When the switch wipers 270-273, are rotated into engagement with a set of bank contacts which are idle there will be no circuit for the test relay 205. Then, following the deenergization 20 of the slow acting relay 205, the switching relay 203 will be energized and the same operations that have been described before will ensue.

25 The relays 300-303, inclusive, are associated with the test contacts of the various lines of the group and are in multiple with the private normal conductors extending from each test contact. Therefore, as each line becomes busy the associated relay will be energized and, when all the trunks of a group become busy the connection between the test contacts associated with the first line of the group will be opened and should the switch 30 wipers of the connector H be rotated into engagement with the first set of bank contacts of a group of lines under these conditions the connector would operate in the same manner as if engagement were made 35 with a private line. As soon as one of the lines of a group becomes idle the associated relay such as relay 301 would deenergize and complete the connection of the two test contacts 275 and 276. The connector would 40 then rotate into engagement with the idle line, all the foregoing operations taking place in the usual manner.

45 It is the usual practice in automatic telephone systems to take the trunk lines which extend to the private branch exchanges from the bank contacts accessible to rotary connector switches. The toll connector H has access to certain of these trunk lines and should the toll operator desire to connect 50 with a subscriber in a private branch exchange she will operate her calling device in accordance with the digits of the number assigned to the trunk line extending to the desired private branch exchange. In response 55 to the operations of the calling device the connection would be set up in the same manner as was described hereinbefore and it will be assumed that the switches D, E, F and H are the ones selected for use in extending the 60 connection to the desired private branch ex-

change trunk line. When the connector H is operated into engagement with the first trunk line going to the branch exchange, if this trunk is busy the connector will automatically operate to select an idle one of the 70 group of trunk lines. Upon being rotated into engagement with an idle trunk the switching relay 203 will be energized and will operate to reverse the battery back over the trunk line comprising conductors 191 and 194 and the electro-polarized relay 103 in the toll transmission repeater E will be operated. Relay 103, upon operating, reverses the battery over the toll service trunk 75 whereby the polarized relay 44 in the repeater D is operated, as is the supervisory control relay 14 in the operator's cord circuit. Relay 14 energizes to light the supervisory lamp L' thereby notifying the toll operator that the connection has been completed. The above operations take place in the same manner as was before described; however, the trunk lines going to the branch exchange are usually provided with a bridged signal across the trunk. This being 80 the case, the battery feed relay 102 in the repeater E will be immediately energized over the connected trunk line, and, upon operating, will complete a local circuit for the line relay 151 of the toll first selector F and 85 place an additional ground on the ringing control conductor 192. In addition, by the operation of relay 102 battery is removed from the toll service trunk comprising conductors 70 and 71 and the bridged supervisory relay 14 in the operator's cord circuit is deenergized to extinguish the supervisory lamp L'. Ordinarily the effacement of this 90 lamp serves to notify the operator that the called subscriber has answered. However, the operator will remember that she has called a private branch exchange and she will then operate the ringing key K⁴ in the same manner as if she were signalling a local 95 party. The alternating current relay 104 in the repeater E will be operated as before described to complete the circuit of the relay 101. Relay 101, upon energizing, removes ground from the ringing control conductor 100 105 110 115 120 125 130 192, at its armature 111 but this is ineffective to open the circuit of the ring cut off relay 208 in the connector H as the ringing control conductor is grounded by the operation of relay 102. A further result of the energization of relay 101 is that the right hand windings of the repeating coil R are disconnected from the trunk conductors extending to the connector at armatures 111 and 112 and the battery feed relay 102 would deenergize were it not for the fact that there is a local circuit completed for it which extends from ground by way of front contact and armature 114, through resistance 137, front contact and armature 113, through the lower right hand winding of the repeat-

ing coil R, armature 124 and its front contact, and thence through the lower winding of the relay 102 to battery. As the relays 101 and 102 are now both energized ringing current from the generator G' is connected to the trunk line extending to the private branch exchange in order to operate the bridged ring down signal thereat. The subsequent operations wherein the connection is completed to the desired called subscriber in the private branch exchange, the conversation completed, and the connection released will take place in the usual manner and need not be described herein.

Having fully described and ascertained the features of the invention what is considered to be new and desired to have protected by Letters Patent will be pointed out in the appended claims.

I claim:

1. In a telephone system, a series of automatic switches and interconnecting trunk lines for extending a talking connection to a called line, one of said switches being a final connector switch, a controlling line relay in said connector in bridge of the associated trunk line, means for automatically reversing the line conductors of said trunk line when the connection to the called line is completed, and means responsive to said reversal for disconnecting said line relay.
2. In a telephone system, a series of automatic switches and interconnecting trunk lines for extending a talking connection to a called line, one of said switches being a final connector switch, a controlling line relay in said connector in bridge of the associated trunk line, means for automatically reversing the line conductors of said trunk line when the connection to the called line is completed, a battery feed relay in another of said switches, means responsive to said reversal for connecting said battery feed relay across the extended talking circuit, and means responsive to the connecting up of said battery feed relay for disconnecting said line relay.
3. In a telephone system, a series of automatic switches and interconnecting trunk lines for extending a talking connection to a called line, one of said switches being a final connector switch, a controlling line relay in said connector in bridge of the associated trunk line, means for automatically reversing the line conductors of said trunk line when the connection to the called line is completed, a battery feed relay in another of said switches, means responsive to said reversal for connecting said battery feed relay across the extended talking circuit in opposition to said line relay, thereby causing said line relay to deenergize, and another relay responsive to the deenergization of said line relay for disconnecting said line relay.

4. In a telephone system, a series of automatic switches and interconnecting trunk lines for extending a talking connection to a called line, one of said switches being a final connector switch, a controlling line relay in said connector in bridge of the associated trunk line, means for automatically reversing the line conductors of said trunk line when the connection to the called line is completed, means responsive to said reversal for disconnecting said line relay, and means in another of said switches for preventing the release of said connector after said line relay has been disconnected.

5. In a toll service trunking system, means for extending a connection from a toll operator's switchboard to a subscriber's line, said connection comprising three inductively connected sections, means for reversing the current flow in the last section when the connection is completed to the called line, means responsive to said reversal for reversing the current in the intermediate section and means responsive to the second reversal for conductively connecting the first section and the intermediate section together.

6. In a toll service trunking system, means for extending a connection from a toll operator's switchboard to a subscriber's line, said connection comprising three inductively connected sections, means for reversing the current flow in the last section when the connection is completed to the called line, means responsive to said reversal for reversing the current in the intermediate section, means responsive to the second reversal for conductively connecting the first section and the intermediate section together, a signal at the switchboard operated by current flow over the two united sections, and means operated when the called subscriber answers for stopping the current flow over the said united sections to efface said signal.

7. In a telephone system, a main exchange and a branch exchange, a trunk line connecting said exchanges and terminating in a repeater in the branch exchange, means including said trunk line and a connector switch in the branch exchange for connecting a calling line in the main exchange with a called line in the branch exchange, a switch control relay in said connector, a battery feed relay in said repeater, means for connecting said relays in a parallel bridge across the called end of the said trunk upon a connection to a called line being completed, and means for then disconnecting said switch control relay.

8. In a telephone system, a series of automatic switches and interconnecting trunk lines for extending a talking connection to a called line, one of said switches being a final connector switch, a controlling line relay in

said connector in bridge of the associated trunk line, means for automatically reversing the line conductors of said trunk line when the connection to the called line is completed, means responsive to said reversal for disconnecting said line relay, and means for preventing the release of said connector after said line relay has been disconnected.

9. In a telephone system, a connector, a switch control relay in the connector controlled by the operator to cause said switch to select a subscriber's line, open contacts at said connector in the conductors leading to the wipers thereof, and a relay automatically controlled by the said switch control relay when the connection to the subscriber's line is completed to disconnect said control relay and close said contacts.

10. In a telephone system, two exchanges, a trunk line connecting said exchanges and terminating in a repeater in the first exchange, means including said trunk line and a connector in the first exchange for connect-

ing a calling line in the second exchange with a called line in the first, a switch control relay in said connector in bridge of the associated trunk line, and means for deenergizing and then disconnecting said relay when the connection to the called line is completed.

11. In a telephone system, two exchanges, a trunk line connecting said exchanges and terminating in a repeater in the first exchange, means including said trunk line and a connector in the first exchange for connecting a calling line in the second exchange with a called line in the first, means for automatically reversing the line conductors of said trunk when the connection is completed, a line relay in bridge of said trunk, a battery feed relay, and a polarized relay responsive to such reversal to cause the battery feed relay to be substituted for the line relay.

In witness whereof, I hereunto subscribe my name this 23rd day of October, 1925.

JOHN WICKS.
